FUSION ABRADING PROCESS FOR SURFACE-WORKING FLAT AND CURVED SURFACES OF METAL BODIES AND APPARATUS FOR CARRYING OUT SAID PROCESS

Werner Osenberg, Gehrden, Germany, assignor to Bisterfeld & Stolting, Radevormwald (Rheinland), Germany, a firm

Filed Oct. 24, 1956, Ser. No. 618,131

Claims priority, application Germany Oct. 24, 1955

10 Claims. (Cl. 51—209)

The present invention relates to a process and apparatus for carrying out said process of working the flat and curved surfaces of metallic bodies by simultaneous thermal and mechanical action by means of a power-driven tool rotating at a high speed within the range of a high energy flow, having finely serrated friction edges and kept very narrow for the purpose of concentrating energy.

The narrow finely serrated friction edges may be arranged at a certain distance apart either on the periphery or concentrically on the side walls of the rotating fusion abrasive tool made from high-resistance steel. In any case, in order to produce a high concentration of energy, not only a high friction edge speed and a strong drive are necessary, but also suitable bearing and feeding forces must be applied so as to convert into a pasty or liquid state, representing the characteristic of the fusion abrading process, the material to be removed from the surface of the workpiece directly below the friction edges, as a result of the concentration of energy. At the same time the liquid material is flung aside or burnt by the teeth, gaps and roughness of the friction edges under the action of the oxygen of the air which is continuously fed to the points of contact by the adhesive effect of the friction edges.

In view of the high energy fed per unit of time, concentrations of heat occur in the vicinity of these contact points and on the one hand increase the abrading performance at the high peripheral and feed speeds and on the other hand prevent useless heat dispersion into the zones adjacent these points, so that the structural spectrum in these zones can only be affected under most unfavorable circumstances in a thin layer which can easily be removed by subsequent or simultaneous grinding.

The principle of utilizing frictional heat for the purpose of removing material has already been applied with success in connection with friction parting discs and fusion band saws. In the case of both types of tools the material becomes pasty or liquid in the incision and is also carried off by fine teeth. It has already been proposed to work the surfaces of workpieces by means of narrow cutting edges impregnated with hard materials and arranged concentrically on the end face of a rotary tool, as in the case of the subject matter of the invention. However, this applies to a grinding process in which the granular hard material embedded in the cutting edges cuts off chips of material. The process according to the invention, on the other hand, utilizes exclusively the friction heat producing a surface liquefaction at the working point. The fine teeth of the friction edges, which on becoming blunt can be resharpened at the same time by knurling tools, also remove the liquefied material.

Contrary to the friction parting saws serving for cutting material into lengths and the use of which moreover does not detrimentally affect the structure adjacent the cutting point, the high-speed rotary tool according to the invention operates in most cases in several steps or stages

2

and as a result of the arrangement on the end face of one or more narrow edges enables surface-grinding to be carried out. To render it possible to exert the axial bearing pressures which cause the great accumulation of heat constituting the primary condition for carrying out the fusion abrading process, the end face friction disc can be supported in axial direction not only by its spindle but in addition by means of rollers, balls and the like on its periphery.

10 In order to further increase the amount of material removed by the fusion abrading process it can be converted into an electro-frictional process by introducing electric energy and producing arcs between the end friction disc and the workpiece, or it can be combined with 15 a grinding process operating with loose grit. The grit either loose or in the form of a paste can be introduced either by means of a gaseous or liquid pressure medium through nozzles between the serrated friction or abrading edges, which if necessary are profiled in transverse and longitudinal direction, and the surface of the workpiece, or loose grit is placed in a container closable on all sides and in which the fusion abrading disc, coated by dipping or spraying with a thin elastic layer for reasons of wear, runs and contacts the workpiece, for example 20 a rail, a tube or the like. The container is provided at both ends with packings corresponding to the cross-sectional shape of the profile of, for example, a rail. The workpiece to be worked is pushed through the container by a feeding device and can, if it is a question of a rotary body such as a tube, carry out a circular feed movement 25 at the same time. Inversely the container with the rotary friction disc can also be moved over the workpiece, which in this case is a stationary workpiece.

Known types of grinding tools can also be combined 30 with the fusion abrading disc. Thus it is possible to arrange on the end face of the friction disc concentric with the annular edges only to exert friction, for example two-stepped rings impregnated with abrasive with ceramic or plastic bond, which then exert a cutting effect in addition to the friction effect.

Several embodiments of the invention are illustrated by way of example in the accompanying drawing, in which

Fig. 1 is a side elevation, partly in section, showing a 35 three-step or stage fusion abrading disc, constructed as an end face disc with axial support by means of conical rollers;

Fig. 2 shows a single-step fusion abrading disc in part side elevation;

Fig. 3 shows a four-step fusion abrading disc in part side elevation;

Fig. 4 is a part side elevation of a fusion abrading disc 45 composed of a carrier disc with two two-step friction abrading rings firmly secured on it;

Fig. 5 is a part side elevation of a fusion abrading disc composed of a carrier disc, a two-step friction ring and concentric thereto a second two-step ring saturated with abrasive grit;

Fig. 6a shows in part cross-section a two-step fusion abrading disc with knurling rolled therein;

Fig. 6b is a similar cross-section wherein the webs and their friction edges are inclined to their working plane;

Fig. 7 is a part cross-section showing a two-step fusion abrading disc with rolled-in knurling and recess in the friction edge;

Fig. 8 is a part side elevation of a fusion abrading disc 55 with friction edge interrupted by a gap;

Fig. 9 shows a fusion abrading tool with friction discs of different diameters arranged parallel to each other and maintained at a distance apart by intermediate spacers;

Fig. 10 shows in part cross-section a two-step fusion

abrading disc with inserted adjustable ring of plastic material;

Fig. 11 shows in bottom plan view a four-step fusion abrading disc wherein loose abrasive grit is fed to the friction zones by nozzles;

Fig. 12 is a side elevation of the four-step fusion abrading disc illustrated in Fig. 11;

Fig. 13 shows the arrangement of a four-step fusion abrading disc serving for working tubes, in a closed container which can be filled with loose abrasive materials, and

Fig. 14 shows the arrangement of a four-step fusion abrading disc serving for working a railway rail, in a closed container which can be filled with loose abrasive materials.

In the drawing 1 designates the fusion abrading disc and 2 the carrier spindle. The carrier spindle 2 is mounted in a strong machine part 3 shiftable in longitudinal direction. The fusion abrading disc 1 may, as shown in Figs. 1 to 5, be constructed as a single or multiple stepped disc by the arrangement of webs 4 carrying the friction edges 13. To enable pressure to be exerted in axial direction on the surface of the workpiece 9 by means of the abrading or friction disc rotating at a high speed, the complete friction disc is additionally supported by means of conical rollers 5 (Fig. 1) which bear against the conical surfaces 6 and 8. 8 is a hardened ground surface of the guide body 7 which is keyed on the spindle 2 and at the same time bears against the shiftable machine part 3 carrying the spindle 2. As shown in Figs. 1 to 3, the webs 4 carrying the friction edges 13 can be made in one piece with the friction disc 1. They may, however, as shown in Figs. 5 and 4, be inserted as two-stepped friction rings 11 and 12 in a carrier disc 10.

The friction process can according to Fig. 5, also be combined with a grinding process. The carrier disc 10 in this case carries, in addition to the two-step friction ring 11, independently adjustable in axial direction as regards its position in relation to the workpiece, also a two-step ceramic or plastic bond grinding ring. The friction ring 11 in this embodiment of the invention, is fixed on the carrier ring 10' which is adjustable relatively to the carrier disc either before or during the grinding operation by means such as those mentioned, for example, in the description of Fig. 10.

As is usual in the case of friction parting discs, the friction edge coming into contact with the workpiece is, as shown in Figs. 6a to 8, provided with a knurling that is with fine toothing 13. The knurling is rolled into the annular webs 4 by a rotary knurling tool under heavy pressure and can be re-rolled as the friction teeth become worn or blunt.

The arrangement of the annular webs 4 need not necessarily be axially parallel. The webs and their friction edges may also be inclined to the working or friction plane, as indicated at 4' in dotted lines in Fig. 6b. By inclining the friction edges 13 and 14, the material of the liquid film forming during the fusion abrading process can be carried off more satisfactorily by a feed movement.

In the case of the simultaneous use of loose abrasive grit, to enable the grit to be carried along in a reliable manner, the knurling can be formed as shown in Fig. 7 so that the friction edge 13 has a depression 14. Furthermore, the annular webs 4, may, as illustrated in Fig. 8, be provided with gaps 28 and the friction edge with undercut portions 15. The arrow in Fig. 8 shows that the friction edge is moved in a direction which produces a pinching effect and therefore conveys the loose abrasive during the movement of the friction edges 13 over the surface of the workpiece. The fine teeth of the friction edges are shown only on the end face of the individual webs in the figures of the drawing, but may also extend partly or entirely across the side walls of the webs. For producing the teeth in this case, the knurling tool

would act not in axial direction to the face of the friction disc but in radial direction thereto. If several webs are provided, the peripheral toothing of the webs would with suitable feed movement, enable a multi-stage abrasion.

The construction of the fusion abrading tool may also be as shown in Fig. 9, wherein several friction discs 40 are arranged parallel to each other on a strong shaft 2 and held at suitable distances apart by spacing members 10. 27. By making the friction discs 40 of different diameters the complete friction tool will be of hyperboloidal shape, so that, for example, when working railway rails, a cambered shape can be produced on the rolling surface of the rail by inclining the whole power-driven tool relatively to the central axis N of the rail, as shown in Fig. 9.

When loose abrasive grit is used at the same time, the carrying along of this grit can also be effected as shown in Fig. 10 by embedding a ring 16 of plastic material in the groove-shaped cavity between the friction edges 13 and 14, which ring can be pushed into the groove by hydraulic means. For this purpose a steel ring 17 is placed in the groove and can be hydraulically shifted by means of pistons 18 in the direction of the working edges 13, 14 of the friction tool. The pressure medium 20 for actuating the pistons 18 can be introduced through the bore 19. The control pressure cylinder for the pressure medium is arranged centrally within the center axis of the friction tool so that the oil pressure can be varied even while the tool is rotating and the ring 16 of plastic material pushed towards the working edges thereof. Thus it is possible for the ring 16 to project beyond the friction edges by a distance H, as shown in Fig. 10. Owing to the plasticity of the ring 16, the loose abrasive grit is continuously fed back to the friction points in the manner necessary when the fusion abrading disc is arranged as shown in Figs. 13 and 14.

The loose abrasive grit can also be forced through nozzles 20' to 20''' between the friction edges 4 and the surface of the workpiece 9, by means of gaseous or liquid pressure media such as oxygen, etc. It is advisable to arrange the pressure nozzles 20' to 20''' tangentially to the friction rings. For the sake of clearness, the pressure nozzle 20 is shown turned in the plane of the drawing in Fig. 12.

The containers 21 of Figs. 13 and 14 can be closed by covers 22 and 23. The whole container is filled with granular abrasive which can evidently also be embedded in a carrier mass. To prevent the loose abrasive from falling out of the container during the grinding process, the container is, according to Fig. 13, sealed in relation to the piece to be worked, in this case a rail, by means of plastic pressure members 24. As can be seen from Fig. 14, this seal can be attained by inflating the packing of plastic material by the application of pressure, for which purpose the packing 24 is provided with hollow spaces 25.

If a tubular body 9 is to be surface-ground as shown in Fig. 14, a slow turning movement in the direction of the arrow and a longitudinal feed movement can be imparted to it, so that it is possible with a rigid housing 21 and stationary friction disc spindle 2 to work the surface of the tube on the one hand by applying the friction abrading process and in addition by a grinding process with simultaneous feed of loose abrasive. When introducing a fresh tube into the container 21, a dummy length 26 is introduced ahead of the front end of the tube so that the beginning of the tube is also cleanly surface-worked.

The loose abrasive grit can, according to Figs. 13 and 14, be removed from the container periodically and freed from metallic impurities. It is evident that a continuous process might be introduced for this purpose and the abrasive grit led off from the container by means of a conveyor worm. It can then be magnetically freed from metallic impurities and returned into the container from above after it has been cleaned.

As shown in Fig. 14, it is advisable to incline the cen-

tral axis of the fusion abrading disc relatively to the surface of the workpiece. The friction edges 4 must then be likewise correspondingly conically bevelled.

In order to protect the friction tool rotating in the abrasive against wear in the constructions illustrated in Figs. 13 and 14, it is advisable to provide the whole metal tool with a coating of elastic material at regular intervals. This coating can be produced by dipping or spraying. At the commencement of the abrading process, the friction edges of the tool immediately become exposed, so that the coating is then only present on the portions of the tool which are not in contact. The arrangement of the fusion abrading tool and its spindle can, especially when loose abrasive is introduced at the same time, also be such that the spindle stands upright and the end friction disc is arranged over it in such a manner that the loose adhesive fills the gaps between the concentrically arranged webs under the effect of gravity and is carried along as the friction disc rotates. It is evident that in this application of the process, wherein the workpiece is located below the friction disc, a closed container, as shown in Figs. 13 and 14, is necessary.

If the friction disc is electrically insulated from the workpiece, electric arcs can be produced between the friction edges and the surface of the workpiece by feeding electric energy, thereby supplementing the heat concentrations and assisting the liquefaction of the surface of the material resulting in an increase in the abrasive performance.

The multi-step or stage friction rings 11 and 12 mounted in a carrier disc 10 according to Fig. 4 can also be built up from multi-step segments, should the production of closed friction rings prove too expensive. These multi-step segments, which may be produced by forging or pressing, are then fitted together in such a manner that continuous circular friction edges are formed.

It is evident that the process according to the invention can be carried out in many ways. Attention is directed to the fact that in the specification only a few solutions of the problem can be given by way of example. The workpieces shown in Figs. 13 and 14 can also be of various shapes. Obviously instead of rails and tubes, also flat materials, sheets, bands, rods, wires and the like, can be worked with the aid of the fusion abrading process.

The process, may, as already mentioned in the description of Fig. 5, be simultaneously combined with a grinding process. This combination is rendered possible in that, when grinding relatively long workpieces, these are first roughly worked by a fusion abrading disc and subsequently fine worked in the same operation by a multiple-step high-speed grinding disc arranged beside the friction disc and brought into contact with the workpiece to remove the ridges produced by the friction process.

I claim:

1. Fusion abrading process for working flat and curved surfaces of metal bodies, comprising pressing on to the surface of the workpiece at least one finely serrated edge of a power-driven tool rotating with circular motion at a high speed within the range of a high specific surface pressure, said edge being narrow for the purpose of concentrating energy, and at the same time imparting a high feed movement at right angles to this bearing pressure.

2. Fusion abrading process as set forth in claim 1, comprising additionally producing electric arcs in the range of the high specific surface pressure by direct feed of elec-

tric energy for the purpose of increasing the concentration of heat.

3. Fusion abrading process as set forth in claim 1, comprising additionally feeding abrasive material into the range of the high energy flow for the purpose of increasing the mechanical abrasive performance.

10 4. Fusion abrading tool for working flat and curved surfaces of metal bodies, comprising at least one finely serrated narrow friction edge forming the end face of annular webs extending coaxially at a distance apart from the end face of a friction tool made of high-resistance steel.

15 5. Fusion abrading tool as set forth in claim 4, wherein the finely serrated friction edges are also provided on a portion of the side walls of the webs.

6. Fusion abrading tool as set forth in claim 4, wherein the finely serrated friction edges are at an incline to the axis of the tool.

20 7. Fusion abrading tool as set forth in claim 4, wherein the friction disc made from high-resistance steel is additionally equipped with rolling bearing on its periphery for taking up the bearing and feeding forces acting in axial direction.

25 8. Fusion abrading tool as set forth in claim 4, wherein the serration of the friction edges of the annular ribs are provided with recesses both in transverse and longitudinal direction for additionally feeding loose abrasive to the contact points by pinching effect.

30 9. Fusion abrading tool as set forth in claim 4, wherein wear-resisting elastic rings adjustable and readjustable in axial direction are fitted in gaps between the webs and friction edges and serve for additionally feeding loose abrasive material.

35 10. Fusion abrading tool as set forth in claim 4, wherein the tool and the workpiece are enclosed on all sides in a container filled with abrasive material into which container the workpiece is pushed during the working operation.
